UNITED STATES PATENT OFFICE.

EMIL WALTHER, OF WERDAU, GERMANY, ASSIGNOR TO F. A. SATTLER, OF NEUKIRCHEN, GERMANY, A FIRM.

CAN-OPENER.

1,008,932.

Specification of Letters Patent. Patented Nov. 14, 1911.

Application filed June 27, 1911. Serial No. 635,627.

To all whom it may concern:

Be it known that I, EMIL WALTHER, a subject of the King of Saxony, residing at Giegelstrasse 8, Werdau, Saxony, Germany, have invented certain new and useful Improvements in Can-Openers, of which the following is a specification, reference being had therein to the accompanying drawing.

The invention is a contrivance for opening conserve and similar boxes with which, as is well-known, a circular knife is applied that is cutting into the tin while being turned. With the box-openers of this kind and hitherto in use, the circular knife is quite firmly situated, and it is for this reason that on the one hand no fixed depth of the cut can be set and on the other hand the knife cannot get over possible obstructions in cutting, such as for instance soldering.

The nature of the invention consists in the advantage that the shaft of the knife admits of being displaced in a perpendicular plane and has the advantage of being movable in the direction of the major axis of the sleeve, the force of a spring tending to move the knife nearer to the rim. After putting the box on a table capable of being perpendicularly adjusted, the axle of the knife is so far lowered through an adjusting-screw that the knife cuts through the tin just at the surface, and the cut is close to the rim of the box. If the axle of the knife is turned while the box is moved at the same time, then the cover is cut out without the formation of burs. The axle of the knife is more or less displaced toward the middle of the box if the knife meets with any obstructions, such as soldering or the like.

The drawing represents such a contrivance for opening conserve and similar boxes in one form of execution.

Figures 1 and 2 are side views of the contrivance with different positions of the single parts. Fig. 3 shows a front view in connection with Fig. 1, and Fig. 4 gives thereto a view from above.

The frame A is so fastened by means of a clamp C, on a plate α as to be removable, and it carries in its upper box-like end a sleeve e, movable in a perpendicular plane around the pin d. Therein rests in an axially movable manner and permanently pressed by spring f toward the right side the axle h of a circular knife i connected with the hand-crank g, the knife serving

in the well-known manner for cutting open the covers of boxes. There is situated closely beneath this knife, the axle of which can be raised or lowered *ad libitum* by means of the screw k, an element supporting in the well-known manner the conserve or similar box m and capable of being easily taken out, as for instance an elastic hoop n, whereby the box is prevented from slipping sidewise while being slowly turned beneath the circular knife, so that accordingly the cover of the box cut out is a circular disk. A table p, capable of being perpendicularly adjusted by means of the toothed mechanism o with several bands q and a movable roll r for the box, as already employed with other box-openers, serves as a support to the box and holds it in such a secure way between the bands referred to and on the roll that even an unskilled person is able to cut out the cover in a thoroughly perfect manner.

If boxes are to be opened that are not circular and have an eight-angled or similar base, then the hoop n is removed in the manner shown by Fig. 2, and the plate u fastened to the bar S, by means of the finger screw t is carried beneath the circular knife, whereupon the box is drawn along against the part v and may be cut open by the rotating knife.

If the depth of the cut is properly set, the cover of a box is easily cut open so that on account of the movability of its axle the knife avoids all obstacles. Moreover the formation of much bur, as is unavoidable with a large depth of the cut, is impossible. The cutting-plane of the circular knife may be also so arranged as to be parallel to the cover of the box, so that the knife cuts into the lateral walling of the box and thus separates the cover. (See position of the box as shown in dotted lines in Fig. 1.)

Patent claims:

1. A can opener comprising a frame, a sleeve pivoted on said frame and rotatable in a vertical plane, a set screw to maintain said sleeve at the desired angle, a shaft disposed lengthwise in said sleeve, a circular cutter on one end of said shaft and a crank on the other end of said shaft, and a vertically adjustable table beneath said cutter, substantially as described.

2. A can opener comprising a frame, a sleeve rotatable in a vertical plane on a pin

on said frame, a set screw to maintain said sleeve in the desired position, a shaft disposed lengthwise in said sleeve, a circular cutter on one end of said shaft, means to 5 rotate said shaft on the opposite end thereof, resilient means permitting axial movement of said cutter, a vertically adjustable table having a roller beneath said cutter, and an 10 expansible can holder adjacent the top of the can, as specified.

3. A can opener comprising a frame, a sleeve rotatable in a vertical plane on a pin on said frame, a set screw to maintain said 15 sleeve in the desired position, a shaft longitudinally disposed in said sleeve, a circular

cutter on one end of said shaft, means to rotate said shaft on the opposite end thereof, resilient means permitting axial movement of said cutter, a vertically adjustable table having a roller beneath said cutter, an expansible can holder adjacent the top of the can, means to removably attach said can holder to said frame and means to hold the side of a can against said cutter, as herein set forth.

In testimony whereof I affix my signature.
EMIL WALTHER.

In the presence of—
J. KLUHPEN,
CHARLES NEUER.
